UNITED STATES PATENT OFFICE.

GEORG ADAM BARTHEL, OF CHICAGO, ILLINOIS.

DESIGN FOR A BASKET.

43,101.

Specification for Design.

Patented Oct. 8, 1912.

Application filed April 10, 1912. Serial No. 689,913. Term of patent 14 years.

To all whom it may concern:

Be it known that I, GEORG ADAM BARTHEL, subject of the Emperor of Germany, and a resident of the city of Chicago, in the county of Cook, in the State of Illinois, have invented a new, original, and ornamental Design for a Basket; and I do hereby declare that the following is a specification thereof, reference being had to the accompanying drawing, forming a part thereof, in which the figure is a perspective view of the design.

I claim:

The ornamental design for a basket, as shown.

GEORG ADAM BARTHEL.
